(57) **CLAIM**

The ornamental design for a knife, as shown and described.

DESCRIPTION

FIG. 1 is a front view of a knife showing my new design; FIG. 2 is a top plan view thereof; FIG. 3 is a bottom plan view thereof; FIG. 4 is a left side view thereof; FIG. 5 is a right side view thereof; FIG. 6 is a cross-sectional view taken along the arrowed line 6-6 of FIG. 1 thereof; and, FIG. 7 is a cross-sectional view taken along the arrowed line 7-7 of FIG. 1 thereof. The broken lines show an unclaimed portion of the knife, and form no part of the claimed design.
